ELEVATOR

Charles E. Ellis, Mahwah, N. J., assignor to Sedgwick Machine Works, Inc., Poughkeepsie, N. Y., a corporation of New York

Application September 9, 1942, Serial No. 457,690

29 Claims.

(Cl. 187—76)

This invention relates to elevators; and within the term "elevator" I include equipment sometimes referred to as "hoists." Various features and aspects of the invention are applicable to different types of elevators used for a variety of purposes. However, the invention will be disclosed as applied to an elevator designed for transferring heavy loads from one level to another. Among the uses for such an elevator is in vehicle terminals where the trucks or busses are stored at a level below the street and are raised to the street level to receive loads and start their runs. Another use is for handling aircraft.

Among the objects of the invention are the provision of a large platform elevator which automatically decelerates the car in an advantageous manner as the car approaches a landing; the provision of supplementary or additional support for a car when at the landing; the provision of means for automatically bringing the additional support into play as the car reaches the landing; the provision of means for locking a car against unintended movement away from a landing; the provision of improved means for automatically cutting off the power and clamping a car to the guide rails upon breaking of the hoisting element; the provision of means for cutting off the power and clamping a car to the guide rails upon the breaking of any one of a plurality of hoisting elements; and the provision of improved means for connecting a car to a link chain or other flexible hoisting element used to lift the car.

Various additional objects of the invention will be apparent to those skilled in the art from a consideration of the following disclosure.

Fig. 1 of the drawings is a largely diagrammatic plan view. The view shows the elevator car at the upper landing and has parts broken away to show elements located at lower levels.

Fig. 2 is a diagrammatic elevational view showing the general arrangement of the elevator, including upper and lower landings or levels.

Fig. 3 is a fragmentary diagrammatic view showing an endless hoisting chain and driving attachment from the chain to the elevator car. The view is taken in general on line 3—3 of Fig. 2.

Fig. 4 is a large diagrammatic plan view showing one corner of the car supported by the supplementary supporting means at a landing.

Fig. 5 is a largely diagrammatic view corresponding to Fig. 4, but showing the supplementary supporting means in disengage position, as when the car is in motion.

Fig. 6 is a fragmentary view, partially in vertical section, showing the car at the upper landing and the corner of the car interlocked to the shaft structure to provide additional support for the car.

Fig. 7 is a detail view, largely in vertical section, showing the interlocking of the car to the shaft structure when the car is at the landing. The view is taken in general on line 1—1 of Fig. 4.

Fig. 8 is a detail view taken in general on the line 8—8 of Fig. 7.

Fig. 9 is a plan view, partially in section, showing a shuttle assembly, or shuttle, which is connected to one of the hoisting chains and which transmits the lifting force from the hoisting chain to the car.

Fig. 10 is a plan view, partially in section, showing an alternative form of hitch for hitching the hoisting chain to the shuttle.

Fig. 11 is a side elevation, partially in section, showing the shuttle assembly, or shuttle, with the hoisting chain attached thereto. The view is from the direction of the arrow 11 in Fig. 9.

Fig. 12 is a front elevation, partially in section, of the shuttle, looking from the direction of the arrows 12 in Figs. 9 and 11.

Fig. 13 is a diagrammatic elevational view showing safety mechanism for automatically clamping the elevator car to the guide rails upon failure of a hoisting chain or a drive chain.

Fig. 14 is a largely diagrammatic detail view showing in elevation a portion of the overspeed governor chain and a lever moved thereby in the event of too rapid descent of the elevator.

Fig. 15 is a largely diagrammatic elevational view showing locking mechanism operable to lock the car against unintended movement away from a landing. This view shows the parts in locking position.

Fig. 16 is a view similar to Fig. 15, but showing the parts in unlocked position.

Fig. 17 is a simplified circuit diagram showing in skeleton fashion some of the electrical operating and control features that may be used in connection with the elevator.

Reference will first be had principally to Figs. 1 and 2. An elevator car 20, shown as a platform type car, is guided for vertical movement in a generally rectangular shaftway which includes lower landing 21 and upper landing 22. The shaft structure which provides the shaftway is of conventional construction and therefore only fragments of the shaft structure are shown in various figures of the drawings. For example, the shaft structure preferably includes four conventional

T-shaped vertical guide rails, one of which is shown at 24 in Fig. 13.

Provision may be made to carry off water dripping from wet vehicles, or from other sources. Figs. 1 and 6 show the edge of the upper landing provided with a gutter 1. This gutter is covered with a flexibly mounted covering strip 2. Strip 2 is amply perforated to allow water to reach the gutter and it projects into overlapping relation with the shaftway. The edge of the car 20 is provided with a gutter 3, partially covered by a perforated strip 4, which has its free edge supported by a perforated gutter partition 5. With the car at the upper landing as shown in Fig. 6, strip 4 underlaps strip 2; and the strips 2 and 4 provide appropriate running surface to pass the wheels of a vehicle over the gutters. Water may be discharged from gutters 1 and 3 in any suitable way (not shown).

Hoisting chains and drives therefor

At one side of the shaftway (see Fig. 2) there are a pair of vertically arranged endless hoisting elements 25 and 26 which are preferably link chains. These hoisting or lift chains run over upper sprocket wheels 25a and 26a, respectively, and over lower sprocket wheels 25b and 26b, respectively. These sprocket wheels are mounted on the shaft structure (see Fig. 3); and preferably the mounting for the lower sprockets 25b and 26b includes conventional means (not shown) for shifting the axle of the sprockets to tighten chains 25 and 26 as they lengthen due to wear at the joints.

In the pit of the elevator there are suitably journaled cross shafts 28 and 29 driven by an electric motor 30 through reduction gear units 31 and 32. Conventional brake mechanism may be provided at 34 and 35 on the motor shaft. On one end of shaft 28 there is a sprocket 28a which is connected by drive chain 27 to a sprocket 36 which is fixed to and drives lower sprocket 25b of lift chain 25. Similarly, one end of shaft 29 is provided with a sprocket 29a which is connected by drive chain 37 with sprocket 38. Sprocket 38 is fixed to and drives lower sprocket 26b of lift chain 26. Chains 27 and 37 may be tightened by idlers 27a and 37a which are mounted for adjustment in the directions indicated by the arrows associated therewith, respectively.

The weight of car 20 is hung onto hoisting chains 25 and 26 through chain hitches H (see also Fig. 3). Thus, the car is raised and lowered by movement of chains 25 and 26 which move in step. To minimize horizontal side thrust on the vertical guide rails for car 20 hoisting chains 25 and 26 are driven in opposite directions as indicated by the arrows in Fig. 2. The movement of shuttles, which will be described later, would otherwise tend to produce a heavy side thrust.

As previously pointed out, hoisting chains 25 and 26 are located at one side of the elevator shaftway. These chains, with their sprockets, drives, and hitches to the car are duplicated at the opposite side of the shaftway. Thus, there are four hoisting chains in all. Upper sprockets for the second set of hoisting chains are indicated at 39 and 40 in Fig. 1. The drives to these duplicate hoisting chains are from the opposite ends of shafts 28 and 29, through sprockets 28b and 29b, drive chains 41 and 42, and sprockets 44 and 45 which are fixed to and drive the lower sprockets of the hoisting chains, respectively.

When the car is moving between the landings 21 and 22 the hitches H are being moved verti-

cally by the hoisting chains at the same speed that the chains move. Thus, the speed of car 20 is then the same as the linear speed of chains 25 and 26. However, as the car approaches a landing, that portion of the chain to which hitch H is attached, changes direction in passing around the sprocket wheel, with the result that the hitch H is given a horizontal component of movement. Thus, the vertical component of movement of the hitch H gradually diminishes, thereby decelerating the car. The upper and lower sprockets of lift chains 25 and 26 are so positioned that the car is appropriately leveled at the landing when the hitch H has passed substantially one-fourth of the way around an upper or lower sprocket, by which time the vertical component of movement of the hitch has been eliminated, or nearly eliminated. If the lower sprockets be shifted downwardly to tighten the lift chain, the electrical control mechanism can be adjusted to stop the car before the hitches H reach lower dead center position.

In order that a hitch H may pass around the sprockets with the chain, the hitch is arranged for both turning and lateral movement with respect to car 20. The structure involved will be more fully described later, but Fig. 3 shows that the hitch H projects from a shuttle assembly, or shuttle, S. This shuttle is adapted to move back and forth on upper rail R₁ and lower rail R₂ both of which rails are attached to the structure of car 20. Through lever action, lifting force from chain 25 is applied upwardly to rail R₁ with a lesser downward force applied to rail R₂. As shown in Fig. 1, there is a shuttle S for each of the four lift chains.

Interlock between car and shaft structure at landing

Referring to Fig. 5, the shuttle S is shown in the position it occupies when hitch H is being moved vertically by the lift chain, the car 20 being between landings. The nearest corner of the car is provided with an engagement assembly E having engagement means adapted to engage with a supporting bracket B that is mounted on the stationary shaft structure near the landing. The assembly E includes a supporting plate 50 attached to the framework of car 20. Beneath this plate and pivoted to it is a triangular, horizontally swinging frame 51 having a projecting axle 52. Axle 52 carries spaced rollers 54 and 55. A connecting rod 56 connects the swinging frame 51 to shuttle S.

As the car 20 approaches the landing, chain hitch H moves toward dead center position on the sprocket, thereby moving the shuttle S to the position shown in Fig. 4. This shuttle movement, through connecting rod 56, swings frame 51 and engages roller 54 with supporting bracket B. As best seen in Figs. 6, 7, and 8, the supporting bracket B has a channel at 57 which receives roller 54. The bottom horizontal wall or shelf 58 of the channel is cam shaped in such manner that the reaction between it and roller 54 results in a wedging action that accurately levels and supports the edge of car 20 at the landing. The cam 58 has a central dwell zone 59 which is occupied by roller 54 when the car is at rest at the landing.

As the axle 52 is swung into engaged position shown in Fig. 7, roller 55 is confined between bearing plates 60 and 61 which are attached to the structure of car 20. Bearing plate 60 is placeably mounted beneath supporting plate 50.

Bearing plate 61 is replaceably mounted on an I-beam 62 which is part of the framework of car 20.

To lower the car, the direction of the movement of the lift chains is normally reversed. However, harm will not result, if motion is accidentally continued in the same direction, with the result that the hitch H passes entirely over the upper sprocket and descends on the opposite side. In such an event, roller 54 passes out at the opposite end of channel 51 thereby disengaging the car from the bracket B which provides supplemental support at the landing. As shown in Fig. 1 there are four engagement assemblies E, one at each corner of car 20. Each engagement assembly is operated from one of the shuttles S through a connecting rod 56. The shaft structure is, of course, provided with brackets B for all of the engagement assemblies E. As shown in Fig. 2 supporting brackets B may be provided for the different landings, the engagements E cooperating with them at the different landings. In the case of a two landing elevator the brackets B may be eliminated at the lower landing and conventional bumpers or buffers be used for supplementary support when the car is at the lower landing.

Shuttle construction

Reference will be had primarily to Figs. 9, 10, 11 and 12. The shuttle S has a frame designated as a whole by 64, which is of bolted and welded construction. This frame includes vertical wall or web portions 65, 66, 67, 68, 69, 70, 71, and 72; upper horizontal web or body portions 74, 75, 76, and 77; and lower horizontal web or body portions 78, 79, 80, and 83.

A shaft 81 is journalled in the frame, with bearings at 82 and 84. One end of the shaft is provided with a roller 85 which rolls on rail R. Spaced slightly from roller 85 is a washer 86 which is welded to shaft 81 and which limits end play of the shaft. The opposite end of the shaft is enlarged at 87 and socketed to receive stem 88 of chain hitch H. In assembly the socket may be shrunk on stem 88 and then the hitch may be welded to shaft portion 87.

Supported by and spanning the space between vertical frame portions 65 and 66 is an axle 89 on which rotates a roller 90. Supported by and spanning the space between vertical frame portions 67 and 68 is an axle 91 on which rotates a roller 92. Rollers 90 and 92 are beneath, and bear against, upper rail R₁, as shown in Figs. 11 and 12. Four stub axles project upwardly from the shuttle frame and carry rollers 93, 94, 95 and 96, which are adapted to roll on the sides of the head of rail R₁ and thereby keep the shuttle on the track. The shuttle is also provided with pairs of horns 97, 97a, and 98, 98a. The head of rail R₁ is received between the horns of these pairs of horns, as best seen in Fig. 11. The purpose of these horns will be pointed out later.

The appropriate end of the shuttle frame is provided with ears 99 and 100 to which is secured connecting rod 56 that operates engagement assembly E (Figs. 1, 5, and 6). The attachment of rod 56 to the shuttle may be by a bolt 101 having an eccentric portion 102 which passes through rod 56. By turning this bolt to different angular positions, the effective length of rod 56 may be adjusted.

The hitch H is recessed or channeled at 104 and embraces both sides of the hoisting chain C (which may be considered as any one of the four hoisting chains for car 20). Two consecutive

joint pins of the chain are replaced by longer pins 105 and 106 which connect the hitch to the chain. As shown more particularly in Fig. 9 of the drawings, the axis of shaft 81 lies in the plane established by the axes of chain pins 105 and 106 (see also Fig. 11). Thus, the load is applied directly downward to the center line of the chain, without imposing buckling or kinking forces on the chain. The hitch may be made with a central ball-like movable member 107 which may have a separate segment 107a to facilitate assembly. In assembly, short lengths of chain C are first secured to the movable member 107. The body of the movable member, preceded by segment 107a, is inserted somewhat edgewise into the ball-like socket of hitch H and the parts are then turned to the position shown in the drawings. Then a set screw 108 is inserted to hold the parts assembled. The set screw enters a hole 109 in the segment, this hole being larger than the set screw to thereby permit limited wobbling movement between hitch H and chain C. This available wobbling movement prevents torsional stress from being applied to the chain by hitch H. The hitch H is also disclosed in an application of Alexis W. Lemmon, Serial No. 463,629, filed October 28, 1942.

A modified form of hitch is shown in Fig. 10. Here two consecutive joints of the chain C are pinned to the legs of a yoke 110. The yoke is provided with a stub shaft 111 which pivotally connects it to an arm 112 that extends from stem 88.

The shuttle S is constructed with suitable bearings, grease passages, grease fittings, etc. The various bearings for rollers, shaft, etc., are preferably provided with bushings of bearing material, such as bushings 114 (three shown) in Fig. 9. To avoid confusion, grease passages, grease grooves, and grease fittings have been eliminated from the drawings.

Emergency stopping mechanism

Figs. 13 and 14 show diagrammatically mechanism for cutting off the power and wedging the car 20 (Fig. 1) to the guide rails in the event of breakage of a drive or lift chain or in the event that the elevator overspeeds in descending. Everything shown in these figures is attached to or carried by the structure of the elevator car except the vertical guide rail 24.

Positioned to move adjacent to the guide rail 24 is emergency stop mechanism which automatically wedges the car to the rail when the mechanism is tripped or set into action. This stop mechanism, which is designated as a whole by 124, is conventional and well-known in the elevator art. Briefly, it includes a pair of superimposed rollers (not shown) which are adapted to be wedged by inclined planes on the back of member 125 into locking engagement with the guide rail 24. Normally, these two rollers are spaced from the guide rail, but are adapted to be moved upwardly into locking position by levers 126 and 127, respectively. These levers are pivoted to member 125 at 126a and 127a respectively. The outer ends of these levers are connected together for coordinated movement by a link 128 that is biased downwardly by a spring 129. A pin 130 normally blocks movement of lever 127, thereby holding both levers against movement by spring 129. Upon movement of pin 130 to the right, as indicated by the arrow, lever 127 is freed and spring 129 so moves levers 127 and 126 that they elevate the locking rollers

(not shown) into locking engagement with the guide rail 24. It will be understood that the structure described in this paragraph is conventional and well-known to the elevator art.

A long angle iron 131 spans the space between the two shuttles S on each side of the elevator car 20 (see Fig. 1). Attached to the frame of each of the shuttles S is a short length of angle iron 132 adapted, as hereafter explained, to engage the angle iron 131 (see also Figs. 11 and 12). Upon breakage of a lift chain (e. g., chain 25 in Figs. 2 and 3), or upon breakage of the corresponding drive chain (e. g., the chain 27 in Fig. 2), the lifting force applied to hitch H is removed with the result that the shuttle S drops by gravity away from upper shuttle rail R1. Thus most of the weight of the shuttle is applied through angle iron 132 to angle iron 131 to operate mechanism as will presently be pointed out.

A beam 153 limits the downward movement of the shuttle S as it pivots on lower rail R2. The downward movement of the shuttle may be enough to disengage side rollers 95 and 96 (Fig. 11) and 93 and 94 (Fig. 9) from rail R1. For this reason horns 98, 98a (Fig. 11) and 97, 97a (Fig. 9) are provided to keep the shuttle sufficiently aligned with rail R1.

A long stationary shaft 134, which spans the distance between two shuttles S (and also the distance between two guide rails) at one side of the car 20, has mounted on it a long rotatable sleeve 135. Fixed to the near end of this sleeve is an arm 138. Further down the shaft there is fixed to sleeve 135 the lever 136 which projects both up and down. Lever 136 includes a web 137 the width of which extends lengthwise of shaft 134. At intervals along sleeve 135 there are fixed several arms 133 (one shown) which carry angle iron 131. Thus arms 133, 138, 136 and web 137 all rotate in unison with sleeve 135. A rod 123 projects from a ring 122 which can oscillate on pivot 121. This rod carries a compression spring 120 which bears against web 137 to bias the parts into the position shown.

When angle iron 131 is pulled down by shuttle S it operates through arms 133 to rotate sleeve 135 counterclockwise. This results in counterclockwise rotation of lever arm 138, two way lever 136, and web 137. The movement of arm 138 shifts link 139 in the direction of its arrow and thereby moves lever 140 in a clockwise direction. The movement of lever 140 withdraws pin 130, thereby allowing spring 129 to set the locking rollers (not shown) into locking engagement with guide rail 24 as previously pointed out.

Starting with the parts in the position shown in Figs. 13 and 14, I will now show how the car is stopped in case of overspeed in descending. The elevator is equipped with a conventional overspeed chain 145 (Fig. 14) which passes over top and bottom sprockets (not shown) and drives a conventional governor (not shown) located in the elevator pit. This chain is driven by the movement of the elevator car. If the car overspeeds in descending, the governor acts to stall the overspeed chain 145, with the result that lever 146 will be swung in a clockwise direction. The overspeed chain and the governor just referred to are well known in the art. When lever 146 is swung clockwise, it acts through link 147 to move lever arm 133 downwardly, just as though this lever were moved downwardly by the action of angle 132 on the shuttle. Thus the safety mechanism 124 is tripped in the same manner and the lock-

ing rolls set against the guide rail 24 as previously described.

The far end of sleeve 135 is provided with a duplicate of arm 138 connected to operate duplicate stop mechanism 124 that is associated with the other vertical guide rail that is on the same side of the car. Thus, if either of the shuttles S on the one side of the car drop, or if overspeed chain 145 moves lever 146, sleeve 135 will be rotated and trip the stop mechanism 124 associated with both guide rails on the one side of the car. At the opposite side of the car the mechanism shown in Fig. 13 is duplicated except for the overspeed chain, lever 146 and link 147. This duplicate mechanism is cross-connected by rods 150, 150 to two way lever 136, so that the duplicate mechanism at the opposite side of the car is operated from lever 136. The net result is that the safety stop mechanism 124 at all four guide rails will be tripped by either the action of the overspeed chain or by the dropping of any one of the four shuttles S.

Mechanism for locking the car against unintended movement away from the upper landing

This is shown in Figs. 15 and 16 wherein the structure 170 is attached to the structure of the elevator shaftway. The locking arms 171 and 172 are adapted to embrace and confine the two chain hitches H at one side of the car when those hitches are at rest in the upper dead center position they occupy with the car at the upper landing (see Fig. 2). Fig. 15 shows the hitches H so confined, the hand lever 174 being in the position shown in full lines. Upon movement of the handle 174 to the position shown in dot-dash lines, link 176 moves to the left, and through connecting link 177 and lever arm 178, swings locking arm 171 upwardly about its pivot 179. At the same time the movement of link 176 swings bell crank lever 180 counterclockwise and through link 181 swings bell crank lever 182 clockwise. This, through link 184 and lever arm 185 swings locking lever 172 upwardly about its pivot 186. The raised or disengaged position of locking arms 171 and 172 is shown in Fig. 16.

The hand lever 174 may be suitably located, as on the landing adjacent to the shaftway. It will be apparent that upon the car reaching the upper landing and the hitches H being in the dead center position shown in Fig. 2, hand lever 174 may be moved to cause locking levers 171 and 172 to embrace the hitches. This prevents the elevator from being set in motion in case somebody or something tries to start it inadvertently or accidentally. Before the elevator is intentionally set in motion, hand lever 174 is moved to the dot-dash position of Fig. 15, thereby lifting the locking arms 171 and 172 from the hitch H as is shown in Fig. 16.

Electrical system

The elevator may be operated by any suitable electrical system having any known desirable operating and control features and characteristics. Accordingly, no attempt has been made to disclose a full fledged electrical system, but Fig. 17 shows in skeleton fashion certain desirable electrical features that may be included in the system.

The motor 30 is a compound direct current motor having a series field 201, a shunt field 202, and an armature 203. The motor is adapted to be set in operation by "up" and "down" push buttons 204 and 205 which may be mechanically interlocked in known fashion so that both push

buttons can not be depressed at the same time. Fig. 17 assumes that the elevator is at rest at the lower landing. Upon depressing "up" push button 204 circuit is made from the positive side of the line, through six safety switches 206a, 206 (four) and 206b, "up" push button 204, conductor 199, and relay winding 207 of the "up" relay to ground, which is the negative side of the line. This operates the "up" relay which holds by circuit from the positive side of the line, safety switches 206a, 206 and 206b, conductor 208, armature 209, conductor 198, switch 210, conductor 199, and relay winding 207 to ground. The shunt field 202 of the motor is energized from the positive side of the line, conductors 211 and 216, armature 212, conductor 214, shunt field winding 202, and conductor 215 to ground. The armature and the series field 201 are energized from the positive side of the line, conductors 211 and 216, armature 217, conductors 218 and 219, armature 203, conductor 220, armature 221, conductor 222, series field 201, and conductor 215 to ground.

The motor is thus set in operation to move the elevator up. When the elevator reaches the upper landing cam 224 (which will be referred to later) opens switch 210. This breaks the holding circuit of the "up" relay, thereby automatically stopping the elevator at the upper landing.

To return the car to the lower landing "down" push button 205 is depressed. This energizes the winding 225 of the "down" relay as follows: Positive side of the line, safety switches 206a, 206 and 206b, conductor 226, "down" push button 205, conductor 227, and the winding 225 of the "down" relay to ground. The "down" relay holds by a circuit from the positive side of the line, safety switches 206a, 206 and 206b, conductors 208 and 228, armature 229, conductor 230, switch 231, conductor 227, and winding 225 of "down" relay to ground. The shunt field 202 is energized in the same direction as for up movement by circuit from the positive side of the line, conductors 211 and 232, armature 233, conductor 234, shunt winding 202, and conductor 215 to ground. The series field 201 is energized in the same direction as for up movement, but armature 203 is energized in the opposite direction. The circuit is from the positive side of the line, conductors 211 and 232, armature 235, conductor 236, armature 203, conductor 219, back contact of armature 221, armature 221, conductor 222, series field 201, and conductor 215 to ground.

The cam 224 may be arranged in any suitable fashion so that it opens switch 210 upon the elevator reaching the upper landing and opens switch 231 upon the elevator reaching the lower landing. This may be accomplished in various ways, as by placing the switches 210 and 231 on the shaft structure and placing the cam 224 on the car to engage the switches at the proper times. I prefer, however, to place both the switches 210 and 231 on the car and to place the cam 224 on one of the chain hitches H. As shown in Figs. 2 and 3, the hitches H are turned upwardly at the upper landing and downwardly at the lower landing. This makes it feasible to so position switches 210 and 231 that, with the cam 224 on the hitch, it will open switch 210 at the top landing and open switch 231 at the bottom landing.

Safety switches 206 are four in number, one being associated with each of the safety stop mechanisms 124 (Fig. 13) for the four guide rails. As shown in Fig. 13, the switch 206 is

adapted to be opened by the action of pin 130 when the pin is moved to the right to release the mechanism which wedges the car to the guide rails. Since there are four switches 206 in series, one associated with each guide rail, the circuit will be broken in the same fashion if any one of the four wedging mechanisms 124 be tripped. Referring to Fig. 17 and to the tracing of the holding circuits for the "up" and "down" relays given above, it will be seen that the safety switches 206 are in the holding circuits for both the "up" and "down" relays. Accordingly the opening of any one of the switches 206 will release either relay that happens to be in operated position and thereby stop motor 30.

Safety switch 206a is associated with the mechanical locking mechanism of Figs. 15 and 16, being arranged to be opened by the mechanical locking mechanism when hitches H are locked against movement. Thus the elevator motor cannot be energized when the lock of Figs. 15 and 16 is in operated position. Safety switch 206b is opened by the conventional overspeed governor (not shown) in case the car overspeeds in descending.

In compliance with the patent statutes I have disclosed the best form in which I have contemplated applying my invention. It will be realized, however, that the invention may be embodied in many specific forms, and therefore the disclosure is to be considered as illustrative of the invention rather than limiting the scope of the same.

What I claim is:

1. In an elevator having a shaft structure including a landing, a car, and mechanism to move the car to the landing; the improvement which comprises: interengageable roller and roller-receiving elements to provide additional support for the car at the landing, one of the elements being mounted on the shaft structure adjacent to the landing and the other element being attached to the car; and means powered by the mechanism which moves the car to the landing and operative to positively engage said interengageable elements.

2. An elevator construction as in claim 1 in which the interengageable elements have a camming action that tends to level the car at the landing.

3. In an elevator having a shaft structure including a landing, a car, and means including a flexible hoisting element to move the car to the landing, the flexible hoisting element having a portion which changes direction as the car approaches the landing; the improvement which comprises: interengageable elements to provide additional support for the car at the landing, one of the elements being mounted on the shaft structure adjacent to the landing, the other element being attached to the car, and both elements being remote from the flexible hoisting element; an actuator connected to said other element and operable to effect engagement of the interengageable elements; and means connecting said actuator to said portion of the flexible hoisting element for operation of the actuator through the change of direction of said portion of the flexible hoisting element as the car approaches the landing.

4. In an elevator having a shaft structure including a landing, a car, and means including a flexible hoisting element to move the car to and from the landing, the flexible hoisting element having a portion which changes direction as the car approaches and leaves the landing; the im-

provement which comprises: interengageable elements to provide additional support for the car at the landing, one of the elements being mounted on the shaft structure adjacent to the landing, the other element being attached to the car, and both elements being remote from the flexible hoisting element; an actuator connected to said other element and operable to effect engagement of the interengageable elements; and means connecting said actuator to said portion of the flexible hoisting element for operation of the actuator through the change of direction of said portion of the flexible hoisting element as the car approaches and leaves the landing to thereby effect engagement and disengagement of said interengageable elements regardless of the direction of travel of the flexible hoisting element.

5. In an elevator having a shaft structure providing a generally rectangular shaft and a landing, a generally rectangular car, and means including four flexible hoisting elements to move the car to the landing, the flexible hoisting elements having portions which change direction as the car approaches the landing; the improvement which comprises: four sets of interengageable elements to provide additional support for the corners of the car when at the landing, one of the elements of each set being mounted on the shaft structure adjacent to the landing and the other element being attached to the car adjacent to a corner thereof, and means connected to said portion of the flexible hoisting element and operable through change of direction of said portions of the flexible hoisting element to effect engagement of the interengageable elements of said four sets of elements.

6. In an elevator having a shaft structure including a landing, a car, and means including an endless flexible hoisting element to move the car to the landing, the flexible hoisting element having a portion which changes direction as the car approaches the landing; the improvement which comprises: a shuttle mounted on the car structure to transmit lifting force to the car, the shuttle being shiftable back and forth with respect to the car, a lifting connection from said portion of the flexible hoisting element to the shuttle whereby the shuttle will shift when said portion of the flexible hoisting element changes direction, interengageable elements to provide additional support for the car at the landing, and an operating connection from the shuttle to engage said elements in response to the shifting movement of the shuttle as the car approaches the landing.

7. Elevator construction as in claim 6, in which the shuttle includes a member journaled on an axis cross-wise of the shuttle movement, and the flexible hoisting element is connected to such member.

8. Elevator construction as in claim 6, in which the shuttle includes a projecting recessed member, and the flexible hoisting element is nested in the recess and connected at both sides to the recessed member.

9. Elevator construction as in claim 6, in which the shuttle is provided with wheels, and the car is provided with rails on which the wheels run.

10. Elevator construction as in claim 6, in which the shuttle includes a yoke pivoted on a stub axle, and the flexible hoisting element is connected to the yoke.

11. Elevator construction as in claim 6, in which the shuttle includes a member journaled on an axis cross-wise of the shuttle movement,

a yoke is pivotally connected to such member on an axis perpendicular to the axis of the member, and the flexible hoisting element is connected to the yoke.

5 12. Elevator construction as in claim 6, in which the flexible hoisting element is a link chain, and the shuttle is connected to the chain at two consecutive joints thereof.

10 13. Elevator construction as in claim 6, in which the flexible hoisting element is a link chain, the shuttle includes a projecting recessed member, the chain is nested in the recess, and both sides of the recess are pivotally connected to the chain at two consecutive joints thereof.

15 14. An elevator comprising: a car, a landing, a pair of flexible hoisting elements, hitches connecting the hoisting elements to the car, wheels over which the hitches pass to substantially dead center position when the car is at the landing, and means to mechanically lock both hitches in such dead center position to thereby prevent the car from moving away from the landing.

16 15. An elevator comprising: a car, a landing, a flexible hoisting element, a hitch connecting the hoisting element to the car, a wheel over which the hitch passes to substantially dead center position when the car is at the landing, and means to mechanically lock the hitch in such dead center position to thereby prevent the car from moving away from the landing.

17 16. In an elevator having a shaft structure including a landing, a car, and means including lift chains to move the car to and from the landing, the chains having portions respectively which change direction as the car approaches and leaves the landing; the improvement which comprises: four lift chains, four sets of interengageable elements to provide additional support for the car at the landing, one element of each set being mounted on the shaft structure adjacent to the landing and the other being attached to the car, four shuttles attached respectively to said portions of the chains and given movement through the changes of direction of said portions of the chains as the car approaches and leaves the landing, and four operating connections from the shuttles to the sets of interengageable elements respectively to engage and disengage the elements in response to said movement of the shuttles.

18 17. In an elevator having a car, and means including a flexible hoisting element to move the car, the flexible hoisting element having a portion which changes direction during part of the car movement; the improvement which comprises: a track on the car adjacent to the flexible hoisting element, a second track on the car removed from the flexible hoisting element and parallel to the first track, a shuttle frame mounted on the car structure to transmit lifting force to the car, the shuttle frame having wheeled engagement with both of said tracks and being shiftable back and forth on said tracks, a member carried by the frame and journaled on an axis crosswise of the shuttle movement, and means connecting said member to the flexible hoisting element.

19 18. In an elevator having a car, and means including a flexible hoisting element to move the car, the flexible hoisting element having a portion which changes direction during part of the car movement; the improvement which comprises: a shuttle frame mounted on the car structure to transmit lifting force to the car, the shuttle frame being shiftable back and forth with

respect to the car; track-and-wheel means on which the shuttle frame is mounted for the shifting movement, said means including first and second tracks located at different distances from the flexible hoisting element; and an operating connection from the shuttle frame to the hoisting element.

19. Elevator construction as in claim 18, in which the first track is close to the flexible hoisting element and the second track is removed therefrom, and the shuttle frame is provided with two wheels running on the first track and with one wheel running on the second track.

20. Elevator construction as in claim 18, in which the first track is close to the flexible hoisting element and the second track is removed therefrom, and the shuttle frame is provided with a wheel engaging the first track upwardly and with a wheel engaging the second track downwardly.

21. In an elevator having a car, and means including a flexible hoisting element to move the car, the flexible hoisting element having a portion which changes direction during part of the car movement; the improvement which comprises: a shuttle frame mounted on the car structure to transmit lifting force to the car, the shuttle frame being individual to said hoisting element and being shiftable back and forth with respect to the car, spaced tracks attached to the car on which the shuttle frame shifts, track-engaging means carried by the shuttle frame and engaging one track from above and the other track from below, and an operating connection from the shuttle frame to the hoisting element.

22. Elevator construction as in claim 21, in which there are a plurality of flexible hoisting elements, and there are shuttle frames and pairs of tracks individual to the respective hoisting elements.

23. Elevator construction as in claim 21, in which the shuttle frame drops away from one track upon failure of the flexible hoisting element.

24. Elevator construction as in claim 21, in which the elevator car is provided with emergency holding means, the shuttle frame drops away from one track upon failure of the flexible hoisting element, and means are provided to initiate the action of the emergency holding means by the dropping of the shuttle frame.

25. In an elevator having a car, and means including a flexible hoisting element to move the car, the flexible hoisting element having a portion which changes direction during part of the car movement; the improvement which comprises: a shuttle frame mounted on the car structure to transmit lifting force to the car, the shuttle frame being shiftable back and forth with respect to the car; a member carried by the frame and journaled on an axis crosswise of the shuttle movement; and a yoke pivoted to the journaled member on an axis crosswise of the axis of the member, the yoke being connected to the flexible hoisting element.

26. In an elevator having a car, and means including a link chain to move the car, the chain having a portion which changes direction during part of the car movement; the improvement which comprises: a shuttle frame mounted on the

car structure to transmit lifting forces to the car, the shuttle frame being shiftable back and forth with respect to the car; and a member carried by the frame and journaled on an axis crosswise of the shuttle movement, said member having a projecting recessed portion, the chain being nested in the recess, and both sides of the recess being pivotally connected to the chain at two consecutive joints thereof; and the axis of said journaled member lying in the plane established by the axes of the two pivotal connections to said chain.

27. In an elevator having a shaft structure including a landing, a car, mechanism to move the car to the landing, and a pair of interengageable elements to provide additional support for the car at the landing, one of said elements being mounted on the car and the other being mounted on the shaft structure; the improvement which comprises: one of the interengageable elements being a receiving member, and the other being a swinging member having a portion which swings into engagement with the receiving member; and power operated means operable to positively move the swinging member into engagement with the receiving member; the receiving member being shaped to receive the swinging member from opposite sides of the receiving member and the swinging member being engageable with the receiving member from either side thereof.

28. In an elevator having a shaft structure including a landing, a car, mechanism to move the car to the landing, and a pair of interengageable elements to provide additional support for the car at the landing, one of said elements being mounted on the car and the other being mounted on the shaft structure; the improvement which comprises: one of the interengageable elements being a receiving member, and the other being a swinging member having a portion which swings into engagement with the receiving member; and power operated means operable to positively move the swinging member into engagement with the receiving member; the receiving member having a cam surface provided with a dwell zone and with vertically-acting camming zones on either side of the dwell zone, and the engaging portion of the swinging member being a cam follower.

29. In an elevator having a shaft structure including a landing, a car, mechanism to move the car to the landing, and a pair of interengageable elements to provide additional support for the car at the landing, one of said elements being mounted on the car and the other being mounted on the shaft structure; the improvement which comprises: one of the interengageable elements being a receiving member, and the other being a swinging member having a portion which swings into engagement with the receiving member; and power operated means operable to positively move the swinging member into engagement with the receiving member; the receiving member having a cam surface provided with a vertically-acting camming zone and a dwell zone, the engaging portion of the swinging member being a cam follower, and the camming zone being shaped to receive such cam follower as the car approaches the landing.
